(57) **CLAIM**

We claim the ornamental design for a pole clamp for medical device, as shown and described.

DESCRIPTION

FIG. 1 is a front right perspective view of a pole clamp for medical device.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a rear left perspective view thereof.

FIG. 9 is another perspective view thereof; and,

FIG. 10 is a further perspective view thereof.

In the drawings, the broken lines are for the purpose of illustrating environment only and form no part of the claimed design.

1 Claim, 9 Drawing Sheets
